(72) Inventor: **Wenhe Su**, Fujian (CN)

Primary Examiner — Cynthia R Underwood

(**) Term: **15 Years**

(57) **CLAIM**

(21) Appl. No.: **29/806,004**

The ornamental design for a foldable storage silicone dinner plate, as shown and described.

(22) Filed: **Aug. 31, 2021**

DESCRIPTION

(51) **LOC (14) Cl.** 07-01

FIG. 1 is a perspective view of a foldable storage silicone dinner plate design showing my new design.

(52) **U.S. Cl.**

FIG. 2 is a front view of a foldable storage silicone dinner plate.

USPC **D7/555**; D7/553.2

FIG. 3 is a rear view of a foldable storage silicone dinner plate.

(58) **Field of Classification Search**

FIG. 4 is a left side view of a foldable storage silicone dinner plate.

USPC D7/555, 558, 587, 505, 553.2; D9/416,

FIG. 5 is a right side view of a foldable storage silicone dinner plate.

D9/500, 429, 428; D30/129, 130, 131

FIG. 6 is a top view of a foldable storage silicone dinner plate.

CPC .. B65D 21/086; A47G 19/2283; A47G 19/03;

FIG. 7 is a bottom view of a foldable storage silicone dinner plate.

A47J 43/0727

FIG. 8 is a perspective view thereof, showing the foldable storage silicone dinner plate in a state of use; and,

See application file for complete search history.

FIG. 9 is another perspective view thereof, showing the foldable storage silicone dinner plate in a folded state of use.
